(57) **CLAIM**

The ornamental design for a fan and fan base assembly as shown and described.

DESCRIPTION

Reproduction 1.1 is a front elevational view of a fan and fan base assembly according to a first embodiment.

Reproduction 1.2 is a rear elevational view thereof.

Reproduction 1.3 is a top plan view thereof.

Reproduction 1.4 is bottom plan view thereof.

Reproduction 1.5 is a right side elevational view thereof.

Reproduction 1.6 is a left side elevational view thereof.

Reproduction 1.7 is a left front perspective view thereof.

Reproduction 1.8 is a right front perspective view thereof.

Reproduction 1.9 is a right rear perspective view thereof.

Reproduction 1.10 is a left rear perspective view thereof.

Reproduction 2.1 is a front elevational view of a fan and fan base assembly according to a second embodiment.

Reproduction 2.2 is a rear elevational view thereof.

Reproduction 2.3 is a right side elevational view thereof.

Reproduction 2.4 is left side elevational view thereof.

Reproduction 2.5 is a left front perspective view thereof.

Reproduction 2.6 is a left rear perspective view thereof.

Broken lines illustrate portions of the fan and fan base assembly that form no part of the claimed design.
